United States Patent Office

Des. 178,978
Patented Oct. 16, 1956

178,978

VELOCIPED

Norman G. Wintermantel, Palos Heights, Ill., assignor to
Junior Toy Corporation, a corporation of Delaware

Application February 28, 1956, Serial No. 40,400

Term of patent 14 years

(Cl. D34—15)

Fig. 1 is a side elevational view of a velocipede, showing my new design; and

Fig. 2 is a rear perspective view thereof, the broken line showing being omitted for convenience of illustration.

The dominant features of my new design are shown in solid lines in the drawing.

I claim:

The ornamental design for a velocipede, as shown and described.
